DESIGN FOR A DRESS ENSEMBLE

Samuel Reich, Chicago, Ill.

Application February 18, 1941, Serial No. 99,076

Term of patent 3½ years

To all whom it may concern:

Be it known that I, Samuel Reich, a citizen of the United States of America, residing in the city of Chicago, county of Cook, and State of Illinois, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a rear view thereof.

Fig. 3 is a fragmentary front view of the dress member of the ensemble.

Fig. 4 is a rear view of Fig. 3.

The characteristic feature of my design resides in the combination on the dress ensemble disclosed of the specific jacket member having the collar lapels and piping around the jacket edges matching the plaid dress member, said dress member having openings at the shoulders trimmed with buttons and piped to match the body of the jacket member, all as shown.

I claim:

The ornamental design for a dress ensemble, as shown and described.

SAMUEL REICH.
